A. REINECKE

VALVE

Filed June 29, 1926

Inventor:
A. Reinecke
by Langen Parry Card & Langen, Atty's.

UNITED STATES PATENT OFFICE.

AUGUST REINECKE, OF FURSTENWALDE, GERMANY, ASSIGNOR TO JULIUS PINTSCH
AKTIENGESELLSCHAFT, OF BERLIN, GERMANY.

VALVE.

Application filed June 29, 1926, Serial No. 119,430, and in Germany July 7, 1925.

This invention relates to valves, and more particularly to that type of valve employed in conjunction with dry gas meters.

It is sometimes usual, for example in 5 the case of gas meters, to employ valves of the flat type, which consist of a gastight material drawn over a resilient wire ring (spring ring). Such valves, particularly if light materials are employed in their 10 construction, show a great tendency to warp or become deformed, i. e., do not remain flat and therefore give rise to leakage; the force provided not being sufficient to press the same tightly on to the seating.

15 The object of the present invention is to overcome this said drawback, and to this end the material is stretched over a short metal cylinder, and is held by a spring ring of the type already in use. Whilst the metal cylinder provides for rigidity or stiffness of the valve and prevents the same from warping, the spring ring causes the material to be quite evenly tensioned even if, 20 after a relatively long period of use, the tensioned material, due to the frequent striking of the valve against the seating, should become stretched or pockers or wrinkles be formed in the same.

According to one form of embodiment 30 two layers of material are laid over the cylinder, the one at the top and the other at the bottom, and sewn together along their peripheries, an expandable and contractible spring ring having previously been interposed between this peripheral seam and the metal cylinder.

According to a further form of embodiment, a transverse strip is cut away from the metal cylinder, and an expandable and contractible spring ring inserted into the metal cylinder in such manner that the breaks in the cylinder and the spring ring come to rest at different points. The gastight material, with the metal cylinder pressed 45 against it is then sewn as in the case of the first form of embodiment, or is drawn over the metal cylinder from the one side and held on the other side by means of threads. The latter method is applicable only to 50 simple valves, whilst double or twin valves

require to have the material sewn along the periphery.

The invention is illustrated by way of example in the accompanying drawing, in which—

Fig. 1 shows in plan and section the first form of embodiment referred to.

Fig. 2 is a similar view of the second form of embodiment.

With reference to the drawing, 1 is the 60 gastight material and 3 the hollow metal cylinder, the latter in the one case having an inwardly disposed annular groove and in the other case an outwardly disposed annular groove 2. 4 shows the point where the 65 two layers of material are joined along their periphery, and 5 is the spring ring, which in the one case encircles the metal cylinder, and in the other case is disposed within the same.

What I claim as new and desire to secure by Letters Patent is:

1. A valve comprising a hollow metal cylinder, gastight material laid over the said cylinder, and an expandable and contractible 70 spring ring for holding the said material in position.

2. A valve comprising a hollow metal cylinder having an annular groove, an expandable and contractible spring ring circumferentially of said cylinder and disposed in said groove, a layer of gastight material covering the top of the cylinder, and a layer of 75 gastight material covering the bottom of the cylinder, said layers joined together 80 along their peripheries to completely enclose the cylinder and ring.

3. A valve comprising a hollow metal cylinder, said cylinder having a transverse strip cut therefrom, a split expandable and contractible spring ring disposed within the 85 said cylinder in such manner that the break in the said cylinder and the break in the ring are disposed at different points, and gastight material completely enclosing the 90 cylinder and ring.

In testimony whereof I have affixed my signature.

AUGUST REINECKE.
